Claims priority, application Brazil July 7, 1955

7 Claims. (Cl. 187—42)

This invention relates to a control for an elevator of the passenger lift type when disabled. More specifically the present invention relates to a system and machine which makes it possible to provide for an emergency manual control of an elevator from the inside of the elevator in case of a stall or accident, thereby allowing the passengers imprisoned in its interior, by their own efforts, to reach a floor level, quickly and safely to thus leave the elevator without any outside help.

If for any reason, such as a break or failure of the electric energy supply, the elevator car stops somewhere along the vertical shaft, it was heretofore necessary, in order to set it manually in motion, that the failure be noticed by someone on the outside, or that an alarm be sounded either vocally or by means of a bell if any electric current is still available. The presence of a qualified person was then required in the engine space or elsewhere to check the cause of the failure and certain types of elevators even require highly specialized personnel to repair and set the elevator back in service. Since the alarm may be sounded by the passengers, it is obvious that this will not always be perceived and noticed, if one considers the possibility of an accident during off hours or in the case of fire. It is also to be considered that the person who is to repair the elevator much reach the engine space which is generally not easily accessible, particularly when all the cars are also out of service. One has to consider also that the repair personnel must ascertain the exact position of the elevator car inside the shaft, and the number of passengers imprisoned therein, in order to estimate whether or not the total weight of the car exceeds that of the counterweight. Depending on this total weight, the car must be moved upwards or downwards. All of this may have to be effected with difficulty, the communication between the passengers and the repair crew to maneuver the car being made possible only by means of signals and knocks, or vocally. One must still consider that the crew which must maneuver the car must reach the engine space or room which is difficult, chiefly when all other cars are also inoperative. In the engine room, the repair crew must work the brake releaser manually, and at the same time must work the motor of the elevator by means of a crank which is inserted in the motor shaft, or by any other similar expedient which in any case demands a considerable and strenuous physical exertion. Thus the motor shaft may be turned in one or in the other direction, depending on whether the car is to be moved up or down, in accordance with its total weight.

It is an object of the invention to provide means in an elevator so that the latter may be operated from the inside of the stalled car, and with such simplicity that any passenger without the least difficulty may operate it. However, in the case of children, or panic-stricken passengers, the elevator car may be controlled from the outside, from the entrance to the building or from any other convenient location. This invention will also prove use-

2

ful in case of fire, when an empty elevator car is to be moved along its shaft.

The fact that according to the invention the movement of the car may be effected by the passengers themselves with ease with the least possible delay and without any external help, is of paramount convenience and importance, in cases of fire or in the absence of skilled or specialized personnel at the moment, in which cases fatal accidents might result.

10 A further object of the present invention is to provide mechanism as a brake releaser operating unit, a connecting unit, a mechanical propelling unit, an automatic clutch unit and an electric propelling unit. This latter may include some parts of the mechanical propelling unit. Although the brake releaser operating unit may, obviously, make the car move as actuated by gravity, it is evident that such course of action is dangerous apart from the limiting movement of the car, which may only travel itself in the direction of the pull of 15 gravity, according to whether its weight exceeds or does not exceed that of the counterweight. A perfect and safe operation which sets the car in motion from any position whatsoever irrespective of where the failure occurred, and with the choice of up or down movement, 20 in accordance with the will of the operator, can only be achieved, however, with the utilization of all the mentioned units, excepting the electric propelling unit, which is provided to save the effort of the operator or to increase the velocity of movement of the elevator car and 25 which is not absolutely essential.

The brake releaser operating unit may consist of any of the usual means of transmissions with linear movement, the operating forces thereof being provided on a movable base, (the elevator car), and wherein said force 30 may be applied to the transmission from any point from said base. Therefore, it may consist of a hydraulic pressure unit wherein the operator from the inside the car actuates a lever connected to a hydraulic pressure cylinder, which latter may be located on the exterior wall 35 or under the floor of the car. The resulting hydraulic pressure is then transmitted through a pipe to a second cylinder located in the engine space, said cylinder operating another lever which will operate the brake releaser.

40 The unit may also consist of a flexible cable confined inside of a flexible conduit and when the operator operates a lever inside the elevator car, said lever displaces the interior cable connected therewith, and thus producing at the other end of the cable a corresponding movement which will be transmitted to another lever to actuate the brake releaser. The ends of the conduit are 45 fixed to the car and to the engine space and it follows adjacent the electric cable of the elevator.

45 A still further object of the invention is to provide 50 a cable vertically extended along the shaft of the elevator, attached at its lower end to the bottom of said shaft, and its upper end provided with a rod and stretched by means of a strong spring.

Another object of the invention is to provide a mechanical propelling unit consisting of a crank situated inside of the elevator car, which by means of a shaft to engage and operate a chain. The chain extends along the shaft of the elevator. By the movement of the chain the latter turns a shaft which sets gears in motion ultimately connected to the motor of the elevator by means of the connecting ring. Said gears comprise a selector so that the car may be raised or lowered in accordance with the will of the operator.

55 A further object resides in the provision of the automatic clutch unit to automatically throw out of gear 60 the mechanical propelling unit when a sudden re-establishment of the electric energy, during the operation of

the machine, again places the motor of the elevator in operative condition thus making the operation of the machine unnecessary. The clutch unit consists of an electromagnet which, at the moment the mechanical propelling unit is engaged to the operating motor, is connected by means of an electric switch to the electric circuit which normally feeds the motor of the elevator. When energy is re-established in this circuit, the electromagnet on receiving said energy, is actuated, thereby attracting a movable piece which will operate levers, thus immediately setting the clutch free.

Further objects will be apparent from the following description when considered in connection with the accompanying drawings in which:

Figure 1 is a diagrammatic view of an embodiment of the invention.

Fig. 2 shows the electric unit and such parts of the mechanical unit necessary for the operation of the elevator.

Figs. 3, 4 and 5 are side elevations partly in section of the detail illustrating the operation of the connecting ring or means in which in Fig. 3 the parts are disconnected, in Fig. 4 the parts are connected and in Fig. 5 the ring is connected and the clutch disconnected.

Fig. 6 is a side elevation partly in section of the brake releasing means.

Fig. 7 is an end view partly in section of a detail,

Fig. 8 is a side view partly in section of the operating crank and its connecting members, and

Fig. 9 is a side view partly in section of a modified brake releaser operating unit.

In the drawings, 1 represents the motor of the elevator 2 the driving shaft, 3 the brake, 4 the casing of the brake releaser, 5 the hydraulic cylinder for the brake releaser, 6 the hydraulic cylinder for the connecting ring, 7 pipe connection, 8 pipe connection, 9 brake releaser operating lever, 10 articulate lever, 11 crank, 12 gear case, 13 and 14 gears, 15 wall of car, 16 and 17 knobs, 18 and 19 return springs, 20 drive shaft, 21 drive shaft case, 22 case's arm, 23 idle sprocket, 24 drive sprocket, 25 compression spring, 26 facets, 27 driving chain, 28 sprocket pulley, 29 shaft, 30 reduction gear, 31 shaft of clutch gears, 32 and 33 clutch gears, 34 and 35 elastic pressure flaps, 36 reduction gears, 37 clutch shafts, 38 master gear wheel, 39 flywheel shaft, 40 flywheel, 41 clutch plate, 42 connecting ring, 43 and 44 connecting gear wheels, 45 fork lever of connecting ring, 46 return spring, 47 clutch pulley, 48 and 49 articulate levers, 50 and 51 articulate levers, 52 electric wiring, 53 electric key operable by 54, 54 hydraulic pipe derivation from 8, 55 drum pulley of elevator cables, 56 armature, 57 electromagnet, 58 retractable pins, 59 flange of brake wheel, 60 brake shoe, 61 brake lining, 62 hinge, 63 and 64 springs, 65 and 66 levers, 67 gripping head, 68 arm (telescope), 69 piston rod, 70 knob, 71 crank connector, 72 pivot, 73 actuating pulley, 74 and 75 idle pulleys, 76 tension spring, 77, 78, 79 and 80 articulate levers, 81 lever, 82 cable, 83 reduction gears, 84 and 85 clutch gears, 86 and 87 shafts, 88 and 89 electric motors, 90 electric battery, 91 electric control switch, 92 connecting ring operating lever, 93 and 94 hydraulic cylinder for the brake releaser, 95 the gear wheel, 96 and 97 electric wiring, 98 and 99 return springs and 100 extension of lever 9a.

What normally occurs when the motor of an elevator stalls is that the brake releaser 4 is automatically put out of action, thus allowing the brake 3 to halt and stall the elevator car.

By the present invention, the operator, if located in the interior of the stalled elevator car actuates the control 92 which actuates the piston in cylinder 94 so that a pressure force is transmitted through the oil pipes or lines 8 to cylinder 6. Said cylinder 6 will actuate the fork lever 45 which will shift the connecting ring 42

laterally over the connecting gear wheel 43, thus effecting a connection between the stalled motor and the machine, through the gear wheels 43 and 44, as clearly shown in Figs. 3 and 4.

The operator will then operate the brake releaser 4 by means of control 9 which will produce a pressure force on the master cylinder 93, and consequently, through pipe 7, a corresponding pressure force in cylinder 5, which as shown in Fig. 6, will operate the levers 65 and 66, thus rendering the brake releaser active. The motor shaft will consequently be allowed to turn in dependence with the movement transmitted thereto by the machine.

The mechanical propelling unit is then operated by the operator as follows: From an appropriate location 15 in the wall of the elevator car a crank is produced and inserted in the end key or square portion 71, Fig. 8. Upon turning said crank 11 the gear wheels 14 and 13 will be rotated and since the latter gear is mounted on the driving shaft 20, the latter is rotated. However, said shaft 20 is mounted in its covering case 21 by means of the compression spring 25 as is more clearly shown in Fig. 7 and the compression spring contacts shaft 20 on a cylindrical section which is cut with facets or flat surfaces in order to present a better grip to the compression spring. 20 The internal wall of the casing 21 is similarly faceted if desired. On both the shaft 20 and its case 21, being rotated about 90°, the knob 70 on the casing 21 will contact either knob 16 or knob 17, according to the direction of rotation of the shaft and its casing. Thus 25 limited, the rotation of the casing 21 will coincide with the correct positioning of sprocket wheels 23 and 24, the former being idly situated on the extremity of the arm 22 and the latter being mounted on the extremity of the driving shaft 20. It is evident that the force applied to the crank will easily overcome the compressing action of spring 25 and therefore driving shaft 20 will proceed to rotate freely inside its casing. It will be observed that the cover or casing 21 will be normally maintained in such a position as to allow the driving chain 27 to pass freely between the two sprocket wheels 23 and 24, as the elevator car is normally running and functioning, and it will be safely maintained in this position by means of springs 18 and 19. When, however, turned about 90° by means of the operation of the crank, 30 the relatively small resistance of these springs 18 and 19 will be overcome, and on said operation ceasing, said springs will immediately bring the casing 21 back to its normal position, thus disengaging sprocket wheels 23 and 24 from the driving chain 27.

The action of the sprocket wheel 24 on the driving chain 27 will rotate the sprocket wheel 28, and this sprocket wheel communicates such movement, through gear 29, and gear wheels 30 to the axle or shaft 31. According to the direction of rotation of the crank 11, 35 the axle 31 will turn clockwise or counterclockwise, and thus one of the two clutch gears 32 or 33, which are mounted on said shaft 31 in opposition to each other, will advance longitudinally along the shaft 31 and will engage gear wheel 95. The clutch gear 32 or 33 will 40 thus act as a selector of the direction of rotation. Upon one of the clutch gears 32 or 33 engaging the gear wheel 95, the movement will be communicated to the master gear wheel 38 through the speed reduction gear wheels 36 and the master gear wheel 38 will rotate the shaft 39 45 of the flywheel 40, which is connected with the clutch plate 41 by means of the engaging pins 58. The clutch plate 41 is mounted on the clutch shaft 37 on which the gear wheel 44 is also mounted. The flywheel 40 receiving rotation from its shaft 39 and as already mentioned, 50 being connected with and to the clutch plate 41, communicates said rotation through said plate and its shaft 37 to the gear wheel 44, which being linked by means of the connecting ring 42 to the connecting gear wheel 43 mounted on the shaft 39 of the motor of the elevator, 55 forces said motor to turn in a direction corresponding to

the direction of rotation of the crank 11, to thereby raise or lower the elevator car in accordance with the will of the operator.

The electric propelling unit may function as follows: After the connection between the stalled motor of the elevator and the machine is made and after the brake releaser is actuated, the operator, on pressing one of the two electric control buttons in control switch 91, situated inside the car of the elevator, according to whether he wishes to raise or lower the elevator, will cause the closing of the electric circuit comprising either the wiring 96 or 97, as the case might be, thus permitting the electric current from the battery 90 to be applied to one of the electric motors 88 or 89. Since said motors have different directions of rotation, they will cause their respective clutch gear mounting shafts 86 or 87 to rotate in one direction or the other. When one of said shafts is rotating, the clutch gear mounted thereon will be shifted so as to engage the gear wheel 83, transmitting thereto the rotation of its corresponding electric motor. Said gear 83 will then cause the rotation of the flywheel 40 and therefore the rotation of the motor of the elevator.

Since these electric motors have a considerable potential, a too abrupt start of the motor of the elevator would be caused on their being actuated, were it not for the fact that the master gear wheel 38 will also be rotated and therefore will cause all speed reduction gear wheels 36 to rotate, and thus it is evident that on overcoming the inertia of said wheels, the initial pull of the electric motor will be adequately weakened.

In the automatic clutch unit, when the operator operates the connecting unit, the pressure force transmitted through pipe 8 is also distributed to pipe 54, to thus turn on the electric switch 53, to thereby close the circuit comprised by the external wires 52, which is dead at the moment, the wires 52a and 52b and the electromagnet 57. From this moment on any re-establishment of the external energy which normally feeds the motor of the elevator, will also act so that the electromagnet will function. When said electromagnet is actuated, it will attract the armature 56, consequently actuating the levers 48 and 49 which are connected with the forks 50 and 51, which latter extend in the grooved cradle pulley 47 which is mounted on the shaft 37. The action of the electromagnet 57 will thus force from it said shaft 37 which will be shifted inside the shaft 39. Since the shaft 37 has the clutch plate 41, mounted thereon, the latter is also shifted away from the electromagnet 57 and consequently from flywheel 40, and therefore, as shown more clearly in Fig. 5, the projecting pins 58 are pulled out from their sockets in the flywheel 40, thus disengaging plate 41 from flywheel 40. In consequence, flywheel 40 will turn freely, while the assembly, plate 41, shaft 37, gear wheel 44 (which is also mounted on shaft 37) stops naturally.

Should the electric current fail again, electromagnet 57 will release armature 56 which, by means of its return spring 98 and 99 will take its normal position, causing plate 41 to re-engage flywheel 40 by means of its pins 58, which are retractable and provided with internal return springs. It is obvious that the automatic clutch unit may operate with any of the two propelling units, i.e. the mechanical or the electrical one.

It will be obvious to those skilled in the art that the controls mounted inside the elevator car may also be mounted externally relative to the shaft of the elevator, and through a wall, thus making it possible for the operation of the mechanism from any convenient location, such as the entrance lobby of the building. To fully understand this modification one has only to consider the vertical wall 15 of the car of the elevator as being the wall separating the lobby of the building from the shaft of the elevator, crank 11 in this case projecting itself in the outside, into the lobby.

Referring to Fig. 9 there is illustrated a modification

of the brake releaser operating unit with its propelling unit showing in detail the brake releaser 4 in cooperation with the shaft 2 of the motor and the brake 3. A cable extends vertically along or adjacent the shaft of the elevator car and is attached at its lower end to the bottom of the shaft of the elevator with the upper end provided with a rod section 81. A strong tension spring 76 is secured to the rod 81 and to the top of the elevator shaft, as shown in Fig. 1. A pulley 73 is mounted on a lever of the brake releaser handle or operator 9 pivoted on the elevator and this pulley is adjacent to though not necessarily in contact with the cable. The pulley is mounted on a right angle lever extension 100 which is outside of the elevator with the control lever end 9 on the inside of the elevator. When the control lever 9a is actuated by means of a pull of the operator to the dot and dash line position, the pulley 73 is forced against the cable 82 to thereby force the cable out of a straight line and overcoming the force of the spring 76. As a result thereof the rod 81 is pulled downward a slight distance to cause the brake releaser 4 to be actuated by means of the levers 77, 78 and 80 to the dot and dash line positions. To facilitate the bending of the cable spaced pulleys 74 and 75 may be suitably secured to the elevator car by brackets and thus an appreciable distortion of the cable 82 may be achieved for actuation of the brake releaser.

I claim as my invention:

1. Mechanism for raising or lowering a stalled or inoperative motor driven elevator having a brake releaser and means connected to and operable from the inside of the elevator to actuate the brake releaser to permit the elevator to be raised or lowered by manual control and operation, said means comprising a driving shaft from the motor, a lever provided on the inside of the elevator, a hydraulic cylinder provided on the outside of the elevator and with the lever connected to the cylinder, brake shoes, a hydraulic pipe connection and a second cylinder with the pipe connecting said hydraulic cylinder to the second cylinder situated near the driving shaft of the motor of the elevator, said second-mentioned cylinder being mechanically connected to the brake releaser so that when said second-mentioned cylinder is actuated by the hydraulic pressure transmitted to it by the first-mentioned cylinder it presses together, one towards the other, and levers for the brake releaser thereby actuating said brake releaser by separating the brake shoes to allow the shaft of the motor of the elevator to rotate.

2. Mechanism according to claim 1, including a selector of direction or rotation comprising an axle with two clutch gears mounted thereon in opposition to each other to be selectively connected with the intermeshing gears as one of said clutch gears advances along its axle according to the direction of rotation imparted to said axle.

3. Mechanism for raising or lowering a stalled or inoperative motor driven elevator having a brake releaser and means connected to and operable from the inside of the elevator to actuate the brake releaser to permit the elevator to be raised or lowered by manual control and operation, said means comprising a driving shaft from the motor, a lever provided on the inside of the elevator, a hydraulic cylinder provided on the outside of the elevator and with the lever connected to the cylinder, brake shoes, a hydraulic pipe connection and a second cylinder with the pipe connecting said hydraulic cylinder to the second cylinder situated near the driving shaft of the motor of the elevator, said second-mentioned cylinder being mechanically connected to the brake releaser so that when said second-mentioned cylinder is actuated by the hydraulic pressure transmitted to it by the first-mentioned cylinder it presses together, one towards the other, levers for the brake releaser thereby actuating said brake releaser by separating the brake shoes to allow the shaft of the motor of the elevator to rotate, a chain vertically disposed in and along the shaft of the elevator, a sprocket wheel at the top and at the bottom of said shaft around which

the chain passes, and means mounted in the car of the elevator and operable to mesh with said chain to move the car.

4. Mechanism according to claim 3, in which said means mounted in the car of the elevator include a crank situated inside the car and a crank operated shaft projecting outside the car and mounting a driving sprocket maintained out of mesh from said chain by means of at least one spring and so that when the force of said spring is overcome by manual rotation of the crank and shaft, the sprocket meshes with said chain which is brought into contact with said sprocket by means of an idle sprocket.

5. Mechanism according to claim 3, in which said idle sprocket is mounted on a casing, said casing enclosing said driving shaft and rotating therewith by means of a compression spring, said idle sprocket being mounted so that its axis and faces are parallel to the axis and faces of the driving sprocket, and being situated on the side of the chain opposite to the driving sprocket and being so situated that, on rotation of said casing, said idle sprocket engages the chain, when said chain acts as a stopper to the rotation of the casing, overcoming the pressure of said compression spring, thereby allowing the driving shaft to rotate freely inside said casing.

6. Mechanism, according to claim 3, in which the movement of the chain is transmitted through a sprocket

situated at the top of the shaft of the elevator and which stretches said chain, to a plurality of intermeshing gears which are provided connected to a connecting gear situated on the same axis, parallel and adjacent, with a second connecting gear mounted on the driving shaft of the motor of the elevator.

7. Mechanism according to claim 3, in which the movement of the chain is transmitted through a sprocket situated at the top of the shaft of the elevator and which stretches said chain to a plurality of intermeshing gears which are provided connected to a connecting gear situated on the same axis, parallel and adjacent, with a second connecting gear mounted on the driving shaft of the motor of the elevator, the connection between both said connecting gears is made by a collar shiftable along its axis which corresponds also to the axis of said connecting gears, its shifting movement being effected by means of a fork actuated from the inside of the car of the elevator by a lever transmitting its action.
